(57) **CLAIM**

The ornamental design for a vaping device, as shown and described.

DESCRIPTION

FIG. 1 is a perspective view of the vaporizer device;
FIG. 2 is a front elevational view of the vaporizer device;
FIG. 3 is a rear elevational view of the vaporizer device;
FIG. 4 is a left side elevational view of the vaporizer device;
FIG. 5 is a right side elevational view of the vaporizer device;

FIG. 6 is a top plan view of the vaporizer device;
FIG. 7 is a bottom plan view of the vaporizer device; and,
FIG. 8 is a front right perspective view of the vaporizer device.

The broken lines in the drawings depict portions of the vaping device that form no part of the claimed design.
